HOIST

Leonard F. Dakin, Pleasantville, N. Y.

Application February 27, 1948, Serial No. 11,490

3 Claims. (Cl. 212—61)

1

This invention relates to elevating devices and more particularly pertains to hoists for raising and lowering materials for buildings and the like.

The invention provides a novel swinging hoist arranged for operation by one man, and which is capable of being suspended from a wall of a building regardless of any projecting cornice or parapet so as to leave the roof or floor with which it is operating unimpeded for working conditions.

The invention will be understood from the following description when considered in connection with the accompanying drawings forming a part thereof, and in which:

Fig. 1 is a perspective view of a hoist embodying the invention;

Fig. 2 is an elevation of the hoist applied to a building wall;

Fig. 3 is a section of the hoist taken on line 3—3 of Fig. 1;

Fig. 4 is a sectional view on an enlarged scale on line 4—4 of Fig. 3;

Fig. 5 is a sectional view on an enlarged scale on line 5—5 of Fig. 3;

Fig. 6 is a perspective view of an offset adapter for the hoist, and

Fig. 7 is a perspective view of a bracket hook for the hoist.

Like characters of reference designate the same parts throughout the several views.

Referring to the drawings, the hoist comprises in general, a hoist bracket A which is arranged to be secured to a wall of a building, and a hoist B which is supported in the bracket A for swinging movement with respect thereto.

The bracket A has an upper triangle made up of the members 10, 11 and 12, and a lower triangle of the same size formed by members 13, 14 and 15. These two triangles are disposed in horizontal planes and are spaced apart by uprights 16, 17 and 18 at the apices of the triangles. Diagonal braces 19 and 20 extend from the two rear apices of the lower triangle to the forward apex of the upper triangle. The bracket is attached to a wall of a building or the like, by two hooks 21 and 22 which are removably secured to the rear apices of the upper triangle. Each hook has a plurality of bolt holes 23 which receive a bolt 24 projecting upwardly from the upper triangle at a rear apex. As shown particularly in Fig. 4, the head of each bolt is welded in the upper end of each upright 16 and 18. The hooks are placed in the proper position on the bracket A for the thickness of the wall with

2

which it is to be used, and the hooks are secured in place by wing nuts 25.

In the form of the invention selected for illustration, the bracket is mounted on a wall having a cornice 26, and a U-shaped offset adapter 27 is bolted to the lower triangle to engage the wall 28 so that the uprights of the bracket will be in vertical positions and thus support the hoist B in vertical position. As shown in Fig. 6, the adapter 27 is provided with a series of bolt holes 29 in each of its legs so that it can be mounted in the desired position on the bracket for cornices or overhangs of different thicknesses. The adapter is secured to the lower triangle by bolts 30 projecting from the lower ends of the uprights 16 and 18, to which the heads of the bolts are welded, and wing nuts 31 threaded on the bolts.

The swinging hoist B comprises a T-shaped tubular member having a standard 34 and a cross-arm 32 at the upper end of the standard and at right angles thereto, and which is braced from the standard by diagonals 33 and 34. The standard is supported on its lower end on a circular bearing plate 35 having a tubular or cylindrical guide 36 of a diameter such that the standard will turn freely thereon and which is welded at its lower end to the plate 35. The standard passes freely through a central opening in a circular guide plate 37 which is welded to the upper triangle of the bracket. A suitable pulley 38 is mounted on one end of the cross-arm 32 and a similar pulley 39 is mounted on the other end of the cross-arm. A rope 40 which passes over both pulleys has a hook 41 at one end for supporting a bucket 42 which is raised and lowered by the operator by pulling in or letting out the other end of the rope.

In use, to raise materials to a floor or to the roof of a building, or to lower debris therefrom, or to accomplish both of these functions at the same time, the bracket A is secured in place to a wall of the building at the desired elevation by means of the bracket hooks 21 and 22 which are first attached to the bracket in the correct positions by the bolts and nuts 24 and 25 for the particular thickness of the wall to which the bracket is secured. With a wall having an offset or a cornice as shown in Fig. 2, the offset adapter 27 will be utilized and attached to the lower part of the bracket in a position such that when it is in contact with the wall, the standard 34 of the hoist will be disposed vertically. With no offset or cornice, it will not be necessary to use the offset adapter, because the uprights 16 and 18 of the bracket will engage

the face of the wall. If not previously mounted on the bracket, the hoist B is placed in position through the guide plate 37 with the lower end of the standard 31 resting on the bearing plate 35 around the pipe bearing 36. The operator of the hoist, standing on the ground, hooks the bucket 42 on the hook 41, and with the cross-arm 32 of the hoist in a position substantially parallel to the face of wall 28, he pulls on the free end of the rope 40 and thereby raises the bucket to the desired height at or above the top of the wall 28. At this height, the operator then moves the bucket end of the arm toward and over the wall 28, by pulling on the rope in a direction away from the face of the wall. The rope is then released until the bucket is resting on the top of the wall, or if additional assistance is available, the bucket may be swung inwardly of the wall to the floor or to a platform or scaffold. After the bucket has been emptied, it is raised by the hoist, the cross-arm is moved by the rope so that the bucket will clear the wall and it is lowered to the ground.

A two-way operation can be effected by having hooks and buckets on both ends of the rope, so that as one bucket is raised the other is lowered and vice versa. With this arrangement, debris can be lowered as material is hoisted.

By suspending the hoist from a wall of a building, the upper floors and roof areas with which the hoist is used are left entirely free for working conditions. Only one man is required to operate the hoist. He pulls the load to the roof or to the top of the parapet area and places the load without the need of an attendant. As previously mentioned, the hoist will provide a two-way operation for materials—hoisting materials while debris is lowered. Additionally, the bracket hooks and the offset adapter are designed so that the hoist can be used with or without any projection of cornice or parapet.

A preferred form of the invention has been selected for disclosure herein. Inasmuch as changes may be made in the form and location of the several parts of the hoist disclosed without transcending the principles of the invention, it will be understood that the invention is not to be limited excepting by the scope of the appended claims.

What is claimed is:

1. A portable hoist adapted to be attached to a wall of a building, comprising a bracket having two triangular sections secured together in superimposed, spaced and aligned relationship, a hook at each end of one side of the upper section for suspending the bracket from said wall, means for detachably securing the hooks in different positions to the upper section to adjust the distance between the outer ends of the hooks and said side of the upper section, a U-shaped adapter detachably secured to the ends of the side of the lower section corresponding to said one side of the upper section, the adapter being securable in different positions to adjust the distance of the part connecting the legs thereof from said corresponding side of the lower section, means at the apices of said sections opposite said one and corresponding sides of the sections for rotatably supporting a standard with its axis in a substantially vertical position, a cross-arm attached at an intermediate point thereof to the upper end of the standard, and a pulley at each end of the cross-arm.

2. A portable hoist adapted to be attached to a

wall of a building, comprising a bracket having two triangular sections secured together in superimposed, spaced and aligned relationship, a hook having a curved portion and a substantially straight portion, the straight portion having apertures spaced approximately along the axis thereof, bolt and nut means for detachably securing the straight portion of a hook at the desired point thereof to each end of one side of the upper section for suspending the bracket from a wall, a U-shaped adapter having spaced legs and a substantially straight portion extending between and approximately normal to the legs, each leg having apertures spaced substantially along the axis thereof, bolt and nut means for detachably securing the legs at the desired points thereof to the ends of the side of the lower section corresponding to said one side of the upper section to space the lower part of the bracket the desired distance from said wall, means at the apices of said sections opposite said one and corresponding sides of the sections for rotatably supporting a standard with its axis in a substantially vertical position a cross-arm attached at an intermediate point thereof to the upper end of the standard, and a pulley at each end of the cross-arm.

3. A portable hoist adapted to be attached to a wall of a building comprising a bracket having two triangular sections secured together in superimposed, spaced and aligned relationship, a hook at each end of one side of the upper section for suspending the bracket from said wall, means for detachably securing the hooks in different positions to the upper section to adjust the distance between the outer ends of the hooks and said side of the upper section, a U-shaped adapter detachably secured to the ends of the side of the lower section corresponding to said one side of the upper section, the adapter being securable in different positions to adjust the distance of the part connecting the legs thereof from said corresponding side of the lower section, a bearing plate at the apex of said lower section opposite the side to which said adapter is secured, a cylindrical guide on the bearing plate, a guide plate having an aperture therein and disposed at the apex of the upper section and above said bearing plate, a tubular standard having its lower end on said bearing plate with said guide in the lower portion of the standard, the standard passing through the aperture in the guide plate and being freely rotatable on the bracket about the longitudinal axis of the standard, a cross-arm attached at an intermediate point thereof to the upper end of the standard, and a pulley at each end of the cross-arm.
